UNITED STATES PATENT OFFICE.

MARY A. GERER, OF DENVER, COLORADO.

BED-DRAPERY FIXTURE.

1,259,011.

Specification of Letters Patent. Patented Mar. 12, 1918.

Application filed February 19, 1917. Serial No. 149,639.

To all whom it may concern:

Be it known that I, MARY A. GERER, a citizen of the United States, residing at Denver, in the county of Denver and State of Colorado, have invented certain new and useful Improvements in Bed-Drapery Fixtures, of which the following is a specification.

My invention relates to bed drapery fixtures, and one object is to produce a simple and inexpensive device of this character adapted to be applied to the head of a bed for supporting the drapery to hide the pillows and give the bed a neat and ornamental appearance.

A further object is to provide an adjustable device of this character which may be lengthened or shortened to fit beds of different widths and one which can also be readily applied to bed posts of various cross sectional areas and configurations.

In order that the invention may be fully understood, reference will now be made to the accompanying drawing, in which:

25 Figure 1 shows a bed provided with my fixture.

Fig. 2 is a broken plan view of the fixture applied to two round bed posts.

Fig. 3 is a side elevation of one of the 30 fastening members whereby the fixture is secured to the bed.

Fig. 4 is a broken plan view of one end of the fixtures applied to a square bed post.

A designates a bed, the head of which embodies two round posts B, to which my fixture is applied.

Said fixture embodies a tubular member 1 reinforced at its free end by a ferrule 2 and removably-secured at its opposite end by a 40 screw 3 in the tubular extension 4 of right angular clamp member 5.

The clamp member 5 is adapted to coact with a flexible member 6 having a series of holes 7, any of which is adapted to pass over 45 a button 8 on the clamp member 5 and thus removably-secure one end of the flexible member 6 to said clamp member 5.

The opposite end of the flexible member 6 has a threaded element 10 fixed thereto and 50 adapted to pass freely through an opening in the end of the clamp member 5 opposite the end containing the button 8. Said threaded element 10 is provided with a thumb nut 11, whereby it may be drawn for-

ward through the opening in the clamp 55 member 5 to cause the same and the coacting member 6 to firmly grip the bed post.

12 designates a rod adapted to telescope into the tubular member 1, so that the fixture may be extended or contracted to fit 60 beds of different widths. The rod 12 like the tubular member 1 is curved backwardly at its fixed end which is secured by a screw 3 to the tubular extension 4 of a clamp member 5, which coacts with a flexible member 6 having holes therein to pass over the button 7 and provided at its opposite end with a threaded element 10 having a thumb-nut 11. As disclosed by the drawing and the 65 description, the parts described by the characters 3 to 11, inclusive, on the rod 12 are duplicates of the correspondingly numbered parts at the rear end of the tubular member 1.

In applying the fixture to either round or 75 square bed posts, the tubular member 1 and the rod 12 are first adjusted longitudinally to allow the clamp members 5 to engage the front sides of said bed posts. The flexible members 6 are then passed around the backs 80 of the posts and hooked over the respective buttons 7, after which the slack in said members 6 is taken up by proper manipulation of the thumb-nuts 11. The threaded members 10 and the holes 7 in the flexible members 85 6 enable the fixture to be applied to a large variety of sizes in bed posts.

From the foregoing description, it is apparent that I have produced a simple and inexpensive fixture which can be readily applied to beds of different sizes, and bed posts of different cross sectional areas and configurations, and while I have shown and described the preferred form of device, I reserve the right to make such changes in the 90 construction, combination and arrangement of parts as properly fall within the spirit and scope of the claim.

Having thus described my invention, what I claim and desire to secure by Letters Patent, 100 is:

In a fixture of the type set forth, a pair of adjustably connected rods each having an out-turned outer end, a clamp for the outer ends of the rods, each clamp including a 105 tubular part rigidly secured over the said outer ends of the rods and having a substantially V-shaped notch in the outer end

thereof, a substantially V-shaped jaw member secured in said notch so as to have the arms of the jaw extend beyond said tubular part, one of said jaws having its outer end 5 extended outwardly and perforated, a button secured to the other jaw, a flexible strap having a series of openings in one end to receive said button, a threaded stem secured to the other end of the strap and received

through said perforation of said jaw extension, and a nut on the threaded stem engaging said jaw extension. 10

In testimony whereof I affix my signature, in the presence of two witnesses.

MARY A. GERER.

Witnesses:

F. C. FISCHER,
L. J. FISCHER.
